(57) **CLAIM**

The ornamental design for a combined wash basin, cup and lid, as shown and described.

DESCRIPTION

FIG. 1 is a perspective view of a first embodiment of a combined wash basin, cup and lid, showing my new design, with the wash basin, cup and opaque lid shown in an exploded view.

FIG. 2 is a perspective view of a second embodiment of a combined wash basin, cup and lid, showing my new design, with the wash basin, cup and opaque lid shown in an exploded view.

FIG. 3 is a perspective view of a third embodiment of the combined wash basin, cup and lid, showing my new design, showing a transparent lid.

FIG. 4 is a perspective view of a fourth of the combined wash basin, cup and lid, showing my new design, showing a transparent lid.

FIG. 5 is a top perspective view of the first embodiment showing the wash basin, shown separately for ease of illustration.

FIG. 6 is a bottom perspective view thereof.

FIG. 7 is a left-side elevational view thereof.

FIG. 8 is a right-side elevational view thereof.

FIG. 9 is a front elevational view thereof.

FIG. 10 is a rear elevational view thereof.

FIG. 11 is a top plan view thereof.

FIG. 12 is a bottom plan view thereof.

FIG. 13 is a top perspective view of the first embodiment showing the cup, shown separately for ease of illustration.

FIG. 14 is a bottom perspective view thereof.

FIG. 15 is a left-side elevational view thereof.

FIG. 16 is a right-side elevational view thereof.

FIG. 17 is a front elevational view thereof.

FIG. 18 is a rear elevational view thereof.

FIG. 19 is a top plan view thereof.

FIG. 20 is a bottom plan view thereof.

(Continued)

FIG. 21 is a top perspective view of the second embodiment showing the cup, shown separately for ease of illustration. FIG. 22 is a bottom perspective view thereof. FIG. 23 is a left-side elevational view thereof. FIG. 24 is a right-side elevational view thereof. FIG. 25 is a front elevational view thereof. FIG. 26 is a rear elevational view thereof. FIG. 27 is a top plan view thereof. FIG. 28 is a bottom plan view thereof. FIG. 29 is a top perspective view of the first embodiment showing the lid, shown separately for ease of illustration. FIG. 30 is a bottom perspective view thereof. FIG. 31 is a top plan view thereof. FIG. 32 is a bottom plan view thereof; and, FIG. 33 is a side elevational view thereof. The broken lines shown in the figures are for the purpose of illustrating portions of the combined wash basin, cup and lid and form no part of the claimed design.
